TELEGRAPH SYSTEM

Edward E. Kleinschmidt, Park Ridge, Ill., assignor to Teletype Corporation, Chicago, Ill., a corporation of Delaware

Application September 20, 1930, Serial No. 483,348

21 Claims. (Cl. 178—4.1)

The present invention relates to telegraph systems. More particularly the invention relates to telegraph relaying and switching systems embodying automatic apparatus for effecting communication between a central station and a plurality of outlying telegraph stations.

In telegraph systems, the present day practice is to receive all the incoming messages for a large city at a central or main distributing station. This central station is connected to a plurality of scattered sub-stations located in various parts of the city by radial telegraph lines. The messages received at the central station are re-transmitted therefrom over one of these lines to the particular sub-station located nearest the final destination of the message and from which the message is transmitted by messenger to its destination. Similarly messages for transmission must be delivered to an outlying sub-station then transmitted to the central station, and then retransmitted to the remote destination.

In order to handle the signalling traffic in such prior systems, a large number of telegraph sets were located at the central stations to receive messages from or send messages to each of these outlying stations, and message delivery service was maintained at sub-stations where messages for outside delivery were received. To handle the message traffic effectively it has been the practice to utilize at central stations, an independent telegraph set for each outlying station which is expensive, or, by complicated switching apparatus the number of sets of apparatus has been reduced.

Inasmuch as the signalling traffic handled at central stations during peak periods is heavy it is desirable to facilitate quick connections from the central station instruments to any sub-station and provide simple and reliable supervision of the sub-station line by the central station operator so as to avoid unnecessary attempts to seize busy lines. Since the signalling traffic varies from a peak load to a comparatively low load, in accordance with the present invention, novel flexible control of the destination of incoming calls at the central station is provided whereby the total traffic may be concentrated upon a minimum number of operators during hours of low traffic, and is distributed or separated into different classes of traffic during hours of heavy traffic.

Accordingly an object of my invention is to provide novel systems and apparatus for handling incoming and outgoing traffic in telegraph central or relay offices.

Another object of the present invention is to provide novel methods and means for separating traffic into classes which may be handled variably as the message traffic varies to secure maximum efficiency and economy of operation.

Still another object of my invention is to provide novel methods and apparatus for routing telegraph traffic at central or relay telegraph stations.

Still a further object of my invention is to provide novel means for providing absolute central office control in a telegraph system of all connections from as well as to all sub-stations, and to provide novel means whereby a connection once made to a sub-station may be released only from the central office regardless of the point of origin of the connection.

Inasmuch as an attendant at the central station may desire to communicate with a particular sub-station at a time when the sub-station is busy, a further object of my invention is to provide novel means for indicating the busy lines, and for checking the identity of any busy line.

In a signalling to a remote printer station, the operator at the remote station may not at the particular moment be at the instrument. For effective service the calling operator, however, must know whether a remote printer is in condition to receive the message. Heretofore it has been necessary to await signalling from the remote operators for such information which results in a great deal of delay in the existing systems.

Accordingly a further object of the present invention is to provide novel means for automatically indicating the condition of sub-station apparatus at the central or relay station.

Further objects of my invention are to provide novel means for maintaining the sub-station motors normally non-operative when no messages are being transmitted therefrom and starting them into operation when the central or relay office is in condition to receive a message; to provide novel audible busy signals in addition to the visible signals at a central office; to provide novel signalling means at sub-stations to indicate that a message is being received; to provide reverting test means by which a central or relay office attendant may determine positively that the sub-station motors are running, and that the selecting elements of the sub-station are working; and to provide novel means for performing all of the above described operations over a single line wire.

Still further objects of the present invention are to provide automatic switching and message distribution systems in which a minimum amount of apparatus is employed to serve any given number of signalling lines, which facilitates quick automatic connection from a sub-station to central or relay station apparatus, provides for simple and reliable supervision of sub-station lines by attendants, provides flexibility in the control of the destination of calls coming to the central or relay station for concentrating the total traffic.

fic upon a small number of operators during hours of low traffic and properly distributing the traffic during hours of heavy traffic; in which complete control of all outlying station telegraph sets is obtained by the central station operator when once a connection is made to an outlying sub-station; in which a busy identification of all the lines in operation is provided at all times; and in which the condition of a remote apparatus is at all times under supervision of an attendant.

Further objects of this invention will appear in the following description of the preferred embodiment of the invention and are such as may be secured by the utilization of the combinations, sub-combinations and principles hereinafter set forth and as defined by the terms of the appended claims.

Referring to the drawings.

Figure 1 shows in diagram a relay station embodying the present invention.

Figure 2 shows in diagram the equipment at outlying stations embodying the present invention.

In the specific embodiment of the invention as shown in the drawings, the central or relay office of Figure 1 is provided with printing telegraph sets 1 and 2 in sufficient numbers to handle the total traffic, and also with automatic switches 4, one for each sub-station line, each to handle the incoming traffic of its line, and with automatic switches 5 sufficient to handle the outgoing traffic of the central station.

The telegraph sets 1 and 2 are identical and each such set comprises power plug 11, ballast resistance 12, sender 13, printer 14, polar relay 15 and switching plug 16, all connected in a series circuit from a source of power to the tip of the plug 16. Points of relay 15 (shown charged and operated in telegraph set 1) control an obvious circuit through the winding of slow-to-release relay 17. Points of relay 17 (shown operated) control an obvious circuit through winding of quick-break relay 18 (shown charged) which closes an obvious circuit for motor 19 to furnish mechanical power required by sender 13 and printer 14. Relay 15 has mechanical biasing spring 20 to open its points when its winding is not charged by current.

Each set has also release key 26 and testing key 27, the latter shunted by resistance 28, and both keys included in a circuit from earth through power plug 11, wire 29, points of relay 17, key 26 and key 27 to body member of switching plug 16.

The printer and/or receiving perforator operated by a selector magnet 14 and the transmitter 13 may be of any type, such as described in the patents to Krum 1,595,472 issued August 10, 1926, and to Kleinschmidt 1,567,392 issued December 29, 1925.

Work tables 31 and 32 are provided identical in apparatus but differing in circuit connections, because the tables are connected electrically in pairs, and external telegraph circuits pass through one table and terminate at the other.

The equipment of each table, 31 and 32, comprises a power jack 36, two switching jacks, 37 for sending and 38 for receiving, a signaling dial 39, a manual ringing key 40 and a busy signal 41. The dial 39 has the resistance 42.

Power jack 36 comprises the contact member 46 connected to earth, and the contact member 47 connected to a source 48 of direct current, earthed. Dial 39 is of well-known telephone type and comprises a pair of contacts 51 normally closed, which may be operated manually in code

manner to give any desired number of consecutive brief breaks, and also a pair of contacts 52 normally open, which are closed at any time that contacts 51 are open.

The telegraphic circuit connections of the pair of work tables 31 and 32 are as follows: a sending telegraphic line wire 55 and its extension 56 are connected in circuit from earth, winding of signal relay 57, wire 58, points of cut-through relay 59, wire 55, points 51 of dial 39 on table 31 normally closed points of manual switch 40, closed points of jack 38 without plug, wire 56, points 51 on table 32, key 40, points of jack 37 condenser 60 to earth. There is no current. This circuit includes busy signal 41 on table 31 shunted by points of jack 37 and also busy signal 41 on table 32 shunted by points of jack 37.

Holding wire 65 and its extension 66, associated with wires 55 and 56, are connected in circuit from an open point of off-normal switch 67, 20 points of slow-release relay 68, points of relay 59, wire 55, to body member of jack 37 on table 31 through points of jack 37 without plug, wire 66, to body member of jack 37 on table 32.

A receiving telegraphic line wire 70 and its extension 71 are connected from an open point on the switch 4, wire 70, points of jack 38 without plug on table 32, wire 71 to tip spring of jack 38 in table 31.

Holding wire 72 and its extension 73, associated with wires 70 and 71, are connected in circuit from an open point on the switch 4, wire 72, points of jack 38 without plug on table 32, wire 73, points of jack 39 on table 31, to earth.

A table such as 31 is associated with each switch such as 5, and a table such as 32 is associated with each circuit wire such as 70. Each table may have extension wires to another table.

To assemble the apparatus for service, portable set 1 is brought to the fixed and wired table 31. Power plug 11 is inserted in power jack 36. Switching plug 16 then may be inserted in jack 37 whereby set 1 may co-operate with switch 5 as a sending set; or in jack 38 whereby set 1 may cooperate with switch 4 as a receiving set. 45 In the figure, set 1 is connected for sending and set 2 for receiving.

When a set as 2 is connected for receiving messages, no action results until a message is about to be received. When a set as 1 is connected for sending, the motor-starting mechanism operates.

When plug 16 is inserted in jack 37, table 31, a circuit for current is established from source 48, jack member 47, plug 11, ballast 12, sender 13, printer 14, relay 15, tip of plug 16, tip spring of jack 37, switch 40, points 51, wire 55, points of relay 59, wire 58, winding of relay 57 to earth. Relay 57 is operated and operates relay 68 over an obvious circuit. Relay 15 is operated (as shown) and operates relay 17 (as shown) which operates relay 18 (as shown) to operate the motor 19. Set 1 now is in control of switch 5 for outgoing messages.

Switch 5 is of well known type as used in telephone systems. It comprises two sets or banks of fixed contact plates, upper bank 76 and lower bank 77. Two movable contacts or wipers 78 and 79 cooperate with the banks 76 and 77 respectively, and each wiper may engage any contact in its bank by being moved in stepping manner, first vertically by mechanical action of vertical magnet 80 and then horizontally by mechanical action of horizontal magnet 81. The wipers 78 and 79 when advanced are held by dogs not shown which may be withdrawn by release magnet 82, 75

when a spring not shown will move the wipers to the left and gravity will move them downward to normal position shown. This switch is well known and is described in further detail in Chapter 3, "Automatic Telephone Practice", published by H. E. Hershey, 1001 W. Van Buren St., Chicago (1920).

Set 1 controls switch 5 through dial 39 and a set of relays shown in the rectangle 83. Slow release relay 68, series relay 84 and busy relay 85 are of the slow-to-release type. The off-normal switch 67 is in the position drawn when the wipers 78 and 79 are normal as shown. At other times, switch 67 has its contacts reversed.

In operation, to cause wiper 78 and 79 to engage contacts 88 and 89, the operator at set 1 manipulates dial 39 to break points 51 three times, meanwhile closing points 52 to preserve current through printer 14 through the circuit, source 48, jack member 47, plug 11, ballast 12, sender 13, printer 14, relay 15, tip of plug 16, spring of jack 37, switch 40, points 52, resistance 42 to earth. Three successive breaks of points 51 releases the armature of relay 57 three times.

First release of relay 57 connects earth through points of relay 57, points of relay 68, points shown closed in switch 67, winding of relay 84, winding of vertical magnet 80 to battery, operating magnet 80 once, operating relay 84, lifting wipers 78 and 79 one step and shifting the points of switch 67. Second and third releases of relay 57 connects earth through points of relay 57, points of relay 68, lowest points of switch 67, points and winding of relay 84, winding of magnet 80 and 35 to battery. Magnet 80 operates twice and wipers 78 and 79 make two more steps upward, thus stopping at the levels of the contacts 88 and 89. Relay 84 releases.

The operator at set 1 now manipulates dial 39 to break points 51 twice, releasing relay 57 twice, and twice closing circuit from earth through points of relay 57, points of relay 68, lowest points of switch 67, points of unoperated relay 84, lowest points of relay 59 and magnet 81 to battery. Magnet 81 operates twice and steps the wipers 78 and 79 two steps to the right, to engage the contacts 88 and 89. As shown, the lower winding of relay 85 is in shunt with the winding of magnet 81 and relay 85 has been operated and now connects source 90 of alternating current through lower points of relay 85, wire 55, points 51, switch 40, signal device 41 (its shunt points in jack 37 now are open) wire 56, points 51 of table 32, switch 40, points of jack 37, condenser 60, to earth.

Should the selected line be busy, an earth connection will be found upon contact 88 as described later. This will energize the upper winding of busy relay 85 over a circuit from battery through upper winding of relay 85, points of relay 85 (operated) wire 91, wiper 79, contact 89 and earth. The continued circuit from source 90 to signal device 41 will operate the device 41 to notify the operator at set 1 that a busy line has been engaged.

Should the line be not previously busy, relay 95 will release its armatures and (assuming that switch 4 pertains to the line selected) then engagement of 79 and 89 will form a circuit from battery through winding of magnet 101, contact points of magnet 101, wire 102, wire 103, winding of cut-off relay 104, wire 105, wire 106, wire 107, contact 89, wiper 79, wire 91, points of released relay 85, upper winding of relay 59 to earth. The current is not enough to operate magnet 101 nor

relay 104 but moves the armature of relay 59 enough to close the circuit of the lower winding of relay 59 whereupon relay 59 operates its contacts fully and is held operated through key 26 by the circuit from battery, lower winding of relay 59, points of relay 59, wire 65, body member of jack 37 on table 31, body member of plug 16, key 21, key 26, points of relay 17, wire 29, plug 11, jack member 46 to earth. This circuit may be opened only by the operator at set 1, 10 by operating key 26 or by removing plug 16.

The full operation of the points of relay 59 connects the wire 65 to the wiper 79 and thus earth from jack 36, through key 26 and wire 65 is connected to wiper 79, contact 89 and through wires 107 and 106 to other contacts as 89 in other switches as 5, thus providing the earth for busy test as mentioned above under the conditions "should the selected line be busy".

The points of relay 59 also open the circuit of 20 rotary magnet 81 to prevent it from moving the wipers 78 and 79 further.

The points of relay 59 also open the circuit of relay 57 and connect the signal wire 55 to the wiper 78 and contact 88 and thence to wire 108, 25 wire 109 and further as will be described in the general description of operation of the system.

Inward service is effected through switch 4 acting under initial control of sub-station 120.

Sub-station 120 comprises sender 121, printer 30 122, points 123, polar relay 125, motor relay 126 and calling key 127, which may be such as the dial 39, all connected from earth to line 130 in series. Points 123 are shunted by points 131. Relay 125 has points to shunt the winding of relay 126 and key 127, or alternatively to shunt the sender 121. Relay 126 when deenergized closes circuit through the winding of relay 133 which in turn closes an obvious circuit to operate the motor 134. A signal device 135 in series with condenser 136 is connected from line 130 to earth. Operation of sub-station 120 will be described in connection with operation of switch 4.

Switch 4 has three levels of contacts 141, 142, 45 143 shown with fifteen contacts in each level, and three double-end wipers 144, 145, 146 engaging respectively one contact in each level at all times. Ratchet 147 steps all wipers and is stepped by pawl 148 on stepping magnet 101. See chapter 11 of the Hershey book cited. 50 Supervisory relay 149 is normally charged. Line relay 150 starts the stepping action of switch 4. Batteries 151 and 152 are reversed in polarity as compared with all other batteries in the figures.

In operation, wipers 144, 145, 146 are normally 55 on their first contacts as shown and relay 149 is normally charged by current from reverse battery 151, winding and points of relay 149, points of relay 104, wire 152, line wire 130, sub-station 120 to earth. This current operates polar relay 125 60 to open its points and charges relay 126.

To call, operator at sub-station 120 opens calling key 127 briefly. Opening key 127 breaks current through relay 149 and releases relay 149, then upon closing key 127 the circuit is through relay 150 instead of relay 149, thus operating relay 150. Stepping magnet 101 operates by current from battery through winding and then points of magnet 101, points of relays 150 and 104, wiper 145 to earth, and it operates repeatedly as long as earth (busy condition) is found on successive contacts of level 142. Earth at wiper 145 has shunted the winding of relay 104, and when that earth is absent the relay 104 will be operated by current from battery through wind- 75

ing and points of magnet 101, wires 102, 103, relay 104, wire 154, points of relay 150 to earth. Relay 104 operates its armatures 157, 158, 159 to close their front points.

5 Armature 157 recharges relay 149 over an obvious circuit. Armature 158 connects earth from points of relay 150 to wiper 145.

Armature 159 closes a telegraph line circuit from battery at receiving table 32, through 10 power plug 11, ballast 12, sender 13, printer 14, relay 15, tip of switching plug 16, receiving jack 38, wire 70, wiper 144, front point and armature 159, wire 153, line wire 130 and sub-station 120 to earth. The current is full telegraphic operating 15 volume and of such polarity that relays 15 and 125 close their points, operating relay 17 and releasing relay 126, thus operating relay 118 and 133 and starting motors 19 and 134. Thus telegraphic communication is established 20 between sub-station 120 and receiving table 32.

Armature 159 stops current in relay 150 but the slow armature of relay 150 does not remove earth from wire 154 until after another earth connection has been supplied to wire 154, from earth at 25 table 32 through power plug 11, wire 29, points of relay 17, key 26, 27, body of plug 16, body member of jack 38, wire 72, wiper 145, armature 158 and front point to wire 154. Thus the relay 104 passes to sole control of key 26 of table 32. The 30 inward message now may be transmitted.

For restoration to normal, key 26 is opened briefly, releasing relay 104, whereupon armature 159 disconnects line 130 from table 32 and connects line 130 to relay 149, restoring the normal 35 supervisory current which has such polarity that polar relay 125 opens its points, removing shunt from relay 126 which operates its points to open relay 133 which opens its points to stop motor 134. Armature 159 stops current in relay 15 which opens its points, releasing relay 17 and 18, thus stopping motor 19.

Armature 157 closes a restoring circuit for stepping magnet 101 through wire 102, back points of relay 150, wire 161, wiper 146, contacts 45 143, wire 162, armature 157 to earth. Magnet 101 operates repeatedly until all wipers reach normal as shown which opens the restoring circuit, thus completing the operation for an inward message.

50 For transmission of an outward message, operator at table 31 dials as described above, connecting wipers 78 and 79 to contacts 88 and 89. Two circuits result, a telegraphic service circuit through wiper 78 and a private circuit through 55 wiper 79.

The private circuit extends from battery, winding and points of magnet 101 (not operating) 60 wire 102, wire 103, relay 104 wires 105, 106, 107, contact 89, wiper 79, points of relay 159, wire 65, jack 67, plug 16, keys 27, 26, points of relay 17, wire 29, power plug 11 and to earth at table 31. Relay 104 operates armature 157 to close its front point and operates armatures 158 and 159 to open their back points but not to close their front points. Armature 159 removes relay 149 from line 130 and armature 157 holds relay 149 charged.

The telegraphic service circuit extends from 70 battery at table 31, through plug 11, ballast 12, sender 13, printer 14, relay 15, tip of plug 16, spring of jack 37, switch 40, points 51, wire 55, points of relay 159, wiper 78, contact 88, wire 108, wire 109, wire 130 and sub-station 120 to earth, 75 operating relays 125, 126 and 133 to start motor

134. Outward messages now may be transmitted.

For restoration to normal, key 26 of table 31 is operated briefly. Key 26 releases relay 104 which permits armature 159 to connect line 130 to relay 149, reversing polarity upon wire 130 and operating relays 125, 126, and 133 to stop motor 5 134. Key 26 also releases relay 59 which charges magnet 82 by current from battery, magnet 82, top points of switch 67, back points of relay 68, back points of relay 59, wire 65, jack 37, plug 10 16, key 27, key 26, points of relay 17, wire 29, plug 11 to earth. Magnet 82 restores switch 5 as has been described.

The general operation of the system as thus far described is as follows: To transmit an inward 15 message, the sub-station or calling operator operates a starting key. The automatic line switch at the relay office allotted to his line is immediately started into operation to select an idle telegraph set. When such a set has been found, a 20 connection is made between the calling and called set. The sub-station motor will start and the operator may then proceed to send the message 25 at once. The simple act of operating a key connects together a sub-station telegraph set and a central station telegraph set which may be a receiving printer and/or a perforator adapted to record the message in form for re-transmission.

This connection may be terminated only by a 30 key at the central station telegraph set, so that the central or relay station attendant may send to the sub-station any inquiry, request or formal acknowledgment of the message before disconnecting the line. In other words, in the specific 35 embodiment disclosed, the central or relay station has at all times, full control of the signalling line, irrespective of whether the connection originated at the central or relay station or at the remote sub-station. This result is accomplished 40 in the specific embodiment disclosed by maintaining the release magnet of the automatic switch independent of sub-station control at all times.

To send a message from the central office to any sub-station to which messages are to be sent, the central station office attendant dials the 45 number of the line on a dial of the telephone type to establish the proper connection. The message may be then transmitted without waiting for any manual response from the sub-station.

Dialing the number operates an automatic 50 switch to select the desired line to the outlying station. When connection is made to the sub-station line, automatic devices at the sub-station operate to start the sub-station motor and to condition the sub-station apparatus to receive 55 the message without cooperation of an attendant. When the connection has been established, with the central or relay station, telegraphic transmission in either direction may be effected, and connection may be released only by the central 60 office operator.

While the signalling traffic is heavy, it is desirable that independent telegraph sets employed for the outgoing signals and for the incoming signals be separately grouped since one receiving operator may attend several machines. When, however, the traffic becomes light, it is preferable to operate two adjacent sets for the two classes of signalling. This change in grouping is accomplished by switch plugs 16 and jacks 70 37 and 38. When a sole operator with a sole sending set is carrying the early morning traffic, all plugs 16 are pulled other than, first, the set in use for sending, and, second, one or more 75

sets adjacent thereto where plugs 16 are in jacks 38 for receiving. When in any receiving circuit both jacks 38 are without plugs, the circuit tests busy to any calling sub-station, the earth at jack 38 of table 31 being connected through wire 73, then jack 38 of table 32, then wire 72 to the contact in level 142 of wiper 145. The facility for regrouping is an operating convenience which adds to the value of the system of this invention.

10 Visual busy signal

Each line as 130 has a lamp as 163 in a lamp bank 164 connected from battery to its private wire as 106. When the line is engaged by any sending table as 31, a circuit for the lamp will be formed, from battery, lamp 163, wire 165, wire 106, wire 107, contact 89, wiper 79, points of relay 59, wire 65, jack 37, plug 16, key 27 shunting resistance 28, key 26, points of relay 17, wire 29, jack 11 to earth. When the line has engaged any receiving table as 32, a circuit for the lamp will be formed, from battery, lamp 163, wire 165, wire 106, wire 105, wire 154, armature 158, wiper 145, wire 72, jack 38, plug 16, key 27 shunting resistance 28, key 26, points of relay 17, wire 29, plug 11 to earth.

During the time that any telegraph sets at the central station and remote station 120 are connected, lamp 163 is illuminated over a circuit as traced above to indicate that the line 130 is busy.

Since, however, a number of lamps may be illuminated it may be desirable for the operator to check the line with which he is connected. This is accomplished by opening and closing key 27 to change the resistance in the circuit of the lamp 163. By observing which lamp flickers by this operation, the dispatcher will be apprised of the line with which he is connected. Further a glance at the lamp bank will protect the operator from wasting time by dialing for a busy line.

Answer-back system

An answer back system whereby the sub-station automatically responds to a test signal from the central office is provided. In the embodiment disclosed the added equipment comprises only the contact 123 which is open when the printer is in the shift position, and the contact 131 which is opened briefly by the act of selection which corresponds to the selection of the letter M. The open interval thus attained corresponds in time value to the spacing interval of the start pulse in a start-stop system. There is no added equipment at the central office.

The operation of the answer-back comprises sending the successive code signals, for example, a shift signal and an M-character signal, in response to which the sub-station automatically transmits an unshift signal. The shift signal has shifted the central office printer and the unshift signal restores the central office printer mechanism to normal which indicates to the central operator that the sub-station selecting devices are operating properly and have received and interpreted properly the signal "shift" and the signal "M".

Calling the sub-station

At sub-station 120, a signalling device 135 which may take the form of the tuned harmonic ringer of telephone party-line practice, is connected in series with condenser 136 from earth to the signaling conductor 130. On each work table 31, 32, is a manual switch 40 adapted to shift the wire 55 or 56 from jack 37 to source 165

of alternating current, and a further manual switch 168 adapted to shift the wire 70 or 71 from jack 38 to source 165.

The line 130 is seized and a message is sent without awaiting response of the sub-station. However, at times, a central office attendant may desire to obtain direct communication with an attendant at a sub-station, as for instance, when an immediate answer to an inquiry is wanted. By operation of manual key 40 at the central station, an audible signal at the sub-station may be sounded. The central office operator being connected with the line through either automatic switch 4 or 5, may sound the signal until the sub-station is operated in response. The signal device 135 of the substation is tuned to respond to the alternating current from source 165 but does not respond to telegraphic service signals.

The central operator further may operate the key either before or after sending a message to sound the signal to call attention to the message.

Busy-signal system

If all the receiving sets at the central station are busy, a busy signal is sent to the sub-station.

In the level 142 of switch 4, fifteen contacts are shown, the fifteenth being shown insulated. In level 141, the fifteenth contact, 171, is connected to source 172 of alternating current.

In the event that all receiving apparatus is busy, the wipers move from contact to contact until they reach their fifteenth contact where they will stop because relay 104 is not shunted and magnet 101 can not operate. Relay 104 operates and connects the calling line 130 to source 172, thus sounding the signal device 135 at sub-station 120 by current over the circuit from source 172, contact 171, wiper 144, armature 159, wire 153, wire 130, condenser 136, signal device 135 to earth. Relay 104 has opened the circuit of the winding of relay 150 which after a brief interval releases its armature and opens the circuit of relay 104 which releases its armatures to stop the signal and to close the restoring circuit for switch 4.

The sub-station attendant then may operate calling key 127 again, either at once or after a suitable interval.

Dial-switch shunt

A dial 39 is provided individual to each work table. The attendant by operating the dial transmits signals to operate the automatic switch 5 and seize a predetermined signaling line extending to an outlying station. Dial 39 is of the usual type employed in automatic telephony and comprises in part a switch 52 which is connected to resistance 42 and to earth for temporarily maintaining a circuit closed through the local telegraph set while the dial opens and closes points 51 for signaling. This avoids any action by the printer 14 which otherwise might result from dialing were the dials to interrupt current through the printer magnets.

General operation with special features

The improved system offers the optimum facility for enabling the central sending operator to do a maximum amount of work. The system of visual busy signals or lamps enables him to avoid loss of time in useless dialing, and, when a desired line is noted as available and is connected by dialing, the automatic starting of the motor at the sub-station enables the central operator to send the message at once without waiting. The an-

swer-back signal gives him confidence in his work and assures him that he is not "sending to the birds."

One receiving operator may serve several receiving sets, and, as each received message is inspected, the operator is not required to recall the sending station since the holding circuit controlled by key 26 will have held the connection in readiness for any inquiry. This feature becomes of material value in the case of a message in which the sending operator has neglected to identify his sub-station.

When a central operator finds a sub-station irresponsive, his procedure is as follows: Operate key 26 and observe the busy-signal variation, to assure his connection to the proper line. Send shift signal and M-character signal and observe the answer-back signal to assure the operating condition of the station. Then operate the audible signal with key 40 or 166 and send messages with sender 13 until the sub-station responds by operating sender 121. There is provided thus an optimum of simple routine tests and signals to attract the attention of the proper sub-station.

Although I have shown my invention as applied to a preferred embodiment thereof, it will be clear that it may be practiced in many other forms and I do not intend to limit myself to the arrangement shown, but only insofar as set forth in the appended claims.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What I claim and desire to secure by United States Letters Patent is:—

45 1. In a signalling system, a central station, a plurality of sub-stations, normally non-operating telegraph apparatus at each of said sub-stations, a single signalling line extending from the central station individual to each of said sub-stations, switching equipment at said central station, normally non-operating telegraph apparatus for outgoing messages at said central station, plug-and-jack switching means for connecting said outgoing telegraph apparatus to said switching equipment, means responsive to said connection for conditioning said outgoing telegraph apparatus for operation, means for variably operating said switching apparatus to select one of said signalling lines individual to a sub-station, 60 means at said sub-station responsive to the selection of said signalling line for conditioning said telegraph apparatus thereat for operation with said central station apparatus, and means operative following the connection with said sub-station whereby the release of said connection is solely under control from said central station.

70 2. In a telegraph system, a first station, a second station, a line connecting said stations, an isochronous-code sender at said first station, a numerical automatic switch at said first station, means to control said switch selectively to connect said sender to said line, a source of alternating current at said first station, a manual key at said first station adapted to connect said source through said switch to said line, and an

audible-signal device at said second station and responsive to said source.

3. In a telegraph system, a first station, a second station, a signalling line connecting said stations, an isochronous-code sender at said first station, a source of alternating current of determined frequency at said first station, a frequency-selection-responsive audible signal device at said second station and responsive to said source, a manual key adapted to connect said source to said signal device, and an automatic non-numerical switch also adapted to connect said source to said signal device.

4. In a telegraph system, a central station, a sub-station, a signalling line connecting said stations, a plurality of telegraph sets at said central station, automatic switching equipment at said central station and controlled by said sub-station to connect said signalling line to one of said telegraph sets, an audible signal at said sub-station, means in said automatic switch to operate said signal automatically in the event that said switch fails to connect said line to one of said telegraph sets, and means to operate said signal manually in the event that said switch shall have connected said line to one of said telegraph sets.

5. In a telegraph switching system, a control station, a sub-station, a line connecting said stations, an alternating-current source at said control station, a frequency-selective signal device at said sub-station and responsive to said source, a manual key at said control station adapted to connect said source to said line, to operate said signal device, and a non-numerical automatic switch at said control station, said switch permanently associated with said line and adapted to connect said source automatically to said line to operate said signal device.

6. In a telegraph system, a central station, a remote sub-station, a signalling line connecting said stations, normally non-operating telegraph apparatus at each of said stations, switching equipment at said central station, means at said sub-station for operating said switching equipment to select said telegraph apparatus at the central station for connection to said signalling line, means responsive to said connection for starting said central and said sub-station telegraph apparatus into operation; means operative in the event that the central station apparatus is all busy for giving an audible indication thereof at said sub-station, and a manual key at said central station for operating said last means as a calling signal.

7. In a telegraph system, a first station, a second station, at said first station, an isochronous-code sender whose speed is based upon a determined frequency of permutation, at said first station, a source of alternating current of another determined frequency, at said second station, a calling signal responsive to said source only, and at said first station a numerical automatic switch, means to control said switch selectively to connect said sender to said line, and a manual key adapted to connect said source and said calling signal.

8. In a signalling system, a central station, substations, a plurality of signalling lines connecting said central station to said substations, each of said signalling lines comprising a single line conductor extending from said central station to one of said substations, telegraph apparatus at said substations including a normally non-operating motor at each substation, a tele-

graph set at said central station, switching means at said central station for connecting said set to a signalling line, means controlled from said central station over said connected signalling line for starting said normally non-operating motor, and means responsive to signals from said set at said central station for indicating at the central station that the substation telegraph apparatus is in operative condition.

9. In a signalling system, a first station, a second station, a single signalling line connecting said stations, isochronous senders and receivers at said stations, and means responsive to control signals from the sender at said first station to cause the receiver at said second station to send an isochronous signal to said first station different from said control signals to indicate that the receiver at said second station is operating in response to signals from said first station.

10. In a signalling system, a first station, a second station, a signalling line connecting said stations, automatic telegraph senders and receivers at said stations, and means responsive only to two complete normal cyclic selective functioning of the receiver at said second station, and effective to send a signal to said first station.

11. In a signalling system, a first station, a second station, a signalling line connecting said stations, isochronous senders and receivers at said stations and connected to said signalling line, and signalling contact-points connected to the receiver at said second station and operable after a complete normal selective cycle of the said receiver and operating to send a complete isochronous signal over said signalling line to the receiver of said first station.

12. In a telegraph switching system, outgoing automatic switches, incoming automatic switches; two operating tables substantially alike, an outgoing service jack upon each table, an incoming service jack upon each table, a telegraph set upon each table and comprising in part a plug adapted for either jack, said sets being alike, so that either set upon either table may be used for outgoing service or for incoming service according to the jack used.

13. In a telegraph system, a substation telegraph set comprising a printer, a code-sender with normally closed electrical contacts, a motor, a calling key with normally closed electrical contacts, a polar relay, and circuits controlled by said relay to start said motor and to shunt said calling key, and, alternatively, to stop said motor and to shunt the contacts of said code-sender.

14. In a telegraph system, a substation telegraph set comprising a printer, a code-sender with normally closed electrical sending-contacts, a calling key with normally closed electrical contacts, a motor, a polar relay, a sole tongue in said relay, two contacts for said tongue, circuits whereby said sole tongue in engagement with one of said contacts operates said motor to render said sender mechanically operable, a shunt circuit closed by said tongue in engagement with said one of said contacts to shunt the contacts of said calling key, and a further shunt circuit closed by said tongue in engagement with the other one of said contacts to shunt the contacts of said sender.

15. In a telegraph system, two service tables, two service jacks one upon each table, a sole

service line connected to both said jacks, two signal devices one for each jack and both connected to said sole service line, and contacts in each jack to render operable its associated signal device when said jack is in service, whereby a suitable electrical signal received over said line will operate the signal device solely at the jack which is then in service.

16. In a printing telegraph set, a line circuit, a transmitter and a receiving printer associated with said line circuit, a selector mechanism in said printer responsive to a controlling signal over said line circuit, and means controlled by a full cyclic operation of said selector mechanism and associated with said transmitter for transmitting a reply signal over said line circuit after the completion of said controlling signal.

17. In a printing telegraph system, a plurality of stations, a line circuit connecting the stations, a transmitter and a receiving printer at one of said stations associated with the line circuit, a selector mechanism for said receiving printer including a plurality of bars each responsive to a code signal over said line circuit, and means controlled upon the selection and operation of a bar of said selector mechanism of said printer for transmitting a code signal to another connected station.

18. In a printing telegraph system, a plurality of stations, a line circuit connecting the stations, a transmitter and a receiving printer at one of said stations associated with the line circuit, a selector mechanism for said receiving printer including a plurality of bars severally responsive each to a variant code signal over said line circuit, a receiving printer at a distant connected station, and means controlled through the selection and operation of a bar of said selector mechanism of said printer for transmitting a code signal effective to operate the receiving printer at the distant connected station.

19. In a signalling system, a central station and a plurality of remote stations each provided with telegraph printers, a plurality of signalling lines extending from the central station to the remote stations, a plurality of telegraph printers at said central station arranged in a predetermined sequence, automatic switching means for invariably connecting incoming calls to the lowest numbered idle printer, and means for automatically starting the motors of the printers at the central and remote stations upon the establishment of said connection.

20. In a telegraph system, a plurality of transmission lines, a central office in which said transmission lines terminate, telegraph apparatus at said central office common to all said lines, a motor for said telegraph apparatus, and a motor-starting mechanism for said motor responsive to conditions established upon any of said lines.

21. In a telegraph system, a central station, a plurality of sub-stations, line circuits terminating at said central station, one for each of said sub-stations, line relays, one for each of said line circuits and controlled by said sub-stations over said line circuits, a printer and control device at said central station, and means for rendering said printer and control device responsive to conditions established by any one of said line relays.
